UNITED STATES PATENT OFFICE.

FRANK L. WATSON, OF WOMER, KANSAS.

DEVICE FOR LIFTING TUBES, TILES, AND THE LIKE.

1,026,536.

Specification of Letters Patent.

Patented May 14, 1912.

Application filed November 11, 1911. Serial No. 659,871.

To all whom it may concern:

Be it known that I, FRANK L. WATSON, a citizen of the United States, residing at Womer, in the county of Smith and State of Kansas, have invented certain new and useful Improvements in Devices for Lifting Tubes, Tiles, and the Like, of which the following is a specification, reference being had to the accompanying drawings.

10 My invention relates to new and useful improvements in the class of devices known as tube clamps and more particularly to a device adapted for use in lifting tubes or tiles of any character, and my object is to 15 provide a device of this character which may be readily inserted within a tube or pipe engaged with the lower edge thereof and raised to correspondingly raise the pipe.

A further object of the invention resides 20 in providing a device having a plurality of arms or hook members adapted to engage the tube or pipe, and a still further object resides in providing means in connection with said arms for the expansion and contraction of the same.

Still another object of the invention resides in providing a device which is extremely simple and durable in construction, inexpensive to manufacture, and one which 30 is very efficient and useful in operation.

With these and other objects in view, my invention consists in the novel features of construction, combination and arrangement of parts as will be hereinafter referred to 35 and more particularly pointed out in the specification and claims.

In the accompanying drawing forming a part of this application, Figure 1 is a side elevation of the device. Fig. 2 is a top plan 40 view thereof.

In carrying out my invention, I shall refer to the drawing in which similar reference characters designate corresponding parts throughout the several views and in which 45 1 indicates a collar of any desired size having formed thereon a plurality of ears 2 arranged in pairs, there being preferably three sets of the same, and pivoted between each pair of ears 2, is an arm 3, the lower or free 50 end of which has formed thereon, a lug or the like 4, whereby said arms 3 may be termed hook members or the like. The collar 1 has secured thereto at diametrically opposite points thereon, the ends of a rope 55 or cable 5, whereby the device may be raised

and lowered, and disposed between the arms 3, is a substantially cone-shaped follower or the like 6 which comprises a lower ring or band 7, a plurality of spokes or the like 8 and a head piece 9. These parts 7, 8 and 9 are all formed integral, the same outlining, as stated above, a substantially cone-shaped member, and formed on the ring or band 7, is a plurality of ears 10 arranged in pairs through which the respective arms 3 are disposed. Bolts 11 extend through the pairs of ears 10, thereby forming guide members of the ears for said arms, and it will be seen that the follower 6 is adapted to be raised and lowered on the arms 3. In order to 60 provide for this raising and lowering of the follower, an eye bolt 12 is swivelly arranged in the head portion 9 of the follower and has engaged therewith, an additional rope or cable 13 which extends through the collar 1, and from this construction, it will be seen that the follower may be readily raised and lowered with respect to the collar 1 by means of the cable 13 and the complete device 65 raised or lowered by means of the cable 5. 70

In operation, should it be desired to remove, or rather lift, a tube, tile or casing such as is used in wells, the complete device is inserted within the tube, tile or casing, as the case may be, and in so inserting this 75 device, the operator first allows the follower 6 to extend to its lowermost position so as to contract the lower ends of the arms 3. The contraction of the arms will permit the device to enter the tube or the like, and the 80 same is then allowed to extend to a point 85 below said tube, whereupon the follower 6 is drawn upwardly by means of the cable 13 which will expand the arms 3 to allow the lug or hook portions 4 at the free ends 90 thereof to extend beyond the outer periphery of said tube, and when the arms have been expanded in this position, the device 95 is then drawn upwardly by means of the cable 5. The lug or hook portions 4 of the 100 arms will then engage the lower peripheral edge of the tubing and as the device is being drawn upwardly by pulling simultaneously upon the cables 5 and 13, it will be seen that the pipe will not alone be drawn upwardly, but that the arms will be retained in their effective positions. When the pipe 105 or tube has been raised, the cable 13 is released to allow the follower to be moved to its lowermost position, which will contract 110

the lower ends of the arms to permit the release of the portions 4 from their engagement with said tube, whereupon the complete device may be readily removed from the tube or pipe.

From the foregoing description, it will be seen that I have provided a simple, inexpensive and efficient means for accomplishing the objects of the invention, but 10 while the elements herein shown and described are well adapted to serve the functions set forth, it is perfectly obvious that various changes in form, proportion and in the minor details of construction may be 15 resorted to without departing from the spirit or sacrificing any of the principles of the invention.

What I claim is:—

1. A device of the class described, comprising a head member, a plurality of arms pivoted thereto and provided with laterally extending portions at their free ends, a follower of cone-shaped design disposed between said arms, guiding means carried on said follower engaging said arms to permit of the sliding movement of said follower thereon, suspension means for the head member, and means to raise and lower said follower.

2. A device of the class described, comprising a collar, a plurality of arms pivoted thereto and said arms being provided with hook members at the free ends thereof, a cone-shaped follower disposed between said arms, said follower having guiding means thereon through which said arms slidably extend, suspension means for the collar and parts carried thereby, and additional means extending through said collar for

raising and lowering said follower with respect to the collar.

3. A device of the class described, comprising a collar, a plurality of arms having one of their ends pivotally secured to said collar, the free ends of said arms being provided with laterally extending hook portions, a cone-shaped follower disposed between said arms, said follower being provided with a plurality of guiding members through which said arms extend, suspension means for said collar and parts carried thereby, and a flexible connection swivelly engaged with said follower extending through said collar to raise and lower the follower with respect to the collar.

4. A device of the class described, comprising a collar, a plurality of arms having one of their ends pivoted thereto, the free ends of said arms being provided with laterally extending hook portions, a cone-shaped follower disposed between said arms, said follower being provided with a plurality of ears arranged in pairs through which said arms extend, bolts extending through each pair of ears to retain the arms between said ears, a flexible connection swivelly engaged with said follower and extending through said collar to raise and lower the follower and correspondingly expand and contract said arms, and suspension means for the collar and parts carried thereby.

In testimony whereof I hereunto affix my signature in the presence of two witnesses.

FRANK L. WATSON.
